UNITED STATES PATENT OFFICE.

LOUISE C. KING, OF CLEVELAND, OHIO, ASSIGNOR TO THE F. W. KING OPTICAL COMPANY, OF CLEVELAND, OHIO, A CORPORATION OF OHIO.

DESIGN FOR A PAIR OF GOGGLES.

52,323.

Specification for Design.

Patented Aug. 27, 1918.

Application filed May 31, 1917. Serial No. 172,113. Term of patent 7 years.

To all whom it may concern:

Be it known that I, LOUISE C. KING, a citizen of the United States, residing at Cleveland, in the county of Cuyahoga and State of Ohio, have invented a new, original, and ornamental Design for Goggles, of which the following is a specification, reference being had to the accompanying drawings, forming a part thereof.

In said drawings, Figure 1 is a front view; Fig. 2 is a top plan view, showing my new design.

I claim:—

The ornamental design for a pair of goggles substantially as shown.

LOUISE C. KING.

Copies of this patent may be obtained for five cents each, by addressing the "Commissioner of Patents, Washington, D. C."
